The ornamental design for a pierceless, clipless earring, as shown and described.

DESCRIPTION

FIG. 1 is a front elevational view of a pierceless, clipless earring showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view shown in a position of use, the broken line showing of an ear is for illustrative purposes only and forms no part of the claimed design.

FIG. 1

FIG. 2

FIG. 3
